UNITED STATES PATENT OFFICE.

THOMAS MERCER ATKINSON, OF CAMBRIDGE, MASSACHUSETTS, ASSIGNOR TO THE ROYSTON PAPER COMPANY, OF MILLTOWN, NEW JERSEY, A CORPORATION OF NEW JERSEY.

APPARATUS FOR AND METHOD OF PRODUCING COLORED NATURE PAPERS.

Application filed December 19, 1921. Serial No. 523,428.

To all whom it may concern:

Be it known that I, THOMAS MERCER ATKINSON, a subject of the King of Great Britain, and a resident of Cambridge, in the 5 county of Middlesex and State of Massachusetts, have invented an Improvement in Apparatus for and Methods of Producing Colored Nature Papers, of which the following description, in connection with the accompanying drawings, is a specification, like characters on the drawings representing like parts.

My invention relates to an apparatus for and process of producing so-called hand-dipped colored papers commonly known as colored nature papers, this application being a continuation of my copending application Serial No. 441,460, filed January 31, 1921. In order that the principles of my 20 invention may be clearly understood I will describe one embodiment thereof selected for the purpose of illustration and shown in the accompanying drawings, in which,

Fig. 1 is a side elevation, parts being 25 shown in section;

Fig. 2 is a detail view on a larger scale.

In producing colored paper of the type above referred to, particularly such as the imported papers commonly known as Der 30 Lieter papers, it has heretofore been the practice to hand-dip sheets of paper in a bath of dye, each sheet being separately treated and hung for drying. Such a method has many disadvantages, from which my new 35 process affords long sought-for relief, avoiding the great inconvenience and expense attendant upon the hand process.

Referring now to Fig. 1, I have shown a frame-work indicated generally at 1 comprising a series of spaced uprights 2, 2 suitably braced and arranged in pairs of unequal heights. The outer or left hand pair of these uprights has journaled therein a holder or unwinding roller 3 which rotatably 45 supports the roll of uncolored paper 4. In each of the remaining pairs of said uprights 2, 2 is rotatably mounted one of the series of stretcher or ironing rollers 5, 5. The strip or run of paper 6 drawn from the roll 4 is passed respectively under and over alternate rollers, which stretch the paper and iron out any unevenness or irregularity.

Beyond the innermost pair of said stretcher rollers is mounted the dye tank 7,

upon a suitable platform 8 forming a part 55 of the framework. Said tank is located at a level below that of the last ironing roller 5, from which the run of paper passes downwardly into the bath of dye in said tank 7 and beneath a roller 9 journaled in the side 60 walls of the tank.

The bath through which the run of paper is drawn is composed of aniline or other dye dissolved in a suitable solvent, such as alcohol. To the solution is preferably added 65 a small proportion of glycerine, approximately five per cent to give the desired flexibility to the colored paper.

Adjacent the tank and at a level somewhat above it is a pair of pressure rollers 10 and 11 rotatably mounted in the uprights 12. These pressure rollers are preferably formed of a hard, smooth-surfaced material such as vulcanized rubber, fibre, or the like. As best seen in Fig. 2, the upper pressure roller 75 10 is journaled at each end thereof in an adjustable bearing block 13 having the guides 14, 14 which are slidable in guideways in the said uprights 12. The cap 15 of each upright 12 is drilled and screw-threaded to receive the adjusting screw 16, the inner end of which carries a head 17. A coiled spring 18 bears at one end upon the bearing block 13 and at its other end upon the head 17. The upper roller 10 is thus 80 adjustable toward and away from the lower roller 11, the pressure between the two rollers being regulated by a turn of the adjusting screw 16. The amount of dye retained by the paper is thus regulatable, and consequently also the shade of color given the paper by a given dye solution and with a given rate of travel of the paper.

Extending upwardly from the inner end of the tank 7 to a point below the pressure 95 rollers is an apron 19 which receives and returns to the tank all excess color squeezed out by the pressure rollers.

After passing through the bath of dye and between the pressure rollers 10 and 11, 100 the run of paper is led into a hot-air box or oven 20 in which it is completely dried. The air in said oven is maintained at a constant heat by the inflow of heated air from the inlets 21, heated air being supplied from a suitable source, not shown. The oven is provided in its upper surface with a suitable outlet and exhaust pipe 22 for conduct-

ing away the foul air and gases. The colored paper travels continuously through the oven and passes above a roller 23 journaled in the rear wall thereof. The extent and rate of travel and the degree of heat are such that the paper has been entirely dried before arriving at said roller 23. It is thus apparent that the moist dyed paper after leaving the pressure rollers 10 and 11 has no contact with any supporting or other surface until said paper has been thoroughly dried.

Beyond the drying oven the run of dyed paper is passed through a series of cooling chambers 24. The air in said chambers is preferably kept in motion by the blower 33 to aid in the cooling. When the blower is employed the chambers 24 desirably are provided with inter-communicating openings 20 (not shown) in the lower portions thereof, the outer wall of the outermost chamber 24 having a similar opening for the exit of the cooling air. Each of said cooling chambers has rotatably mounted therein cooling 25 chamber rollers 25 at the top and the bottom thereof. The strip of paper is festooned about said cooling rollers through successive chambers and is finally led out and wound upon the rewinding roller 26 rotatably 30 mounted in a suitable standard 27.

A suitable source of power such as an electric motor 28 is provided, having a driving connection shown as a belt 29 with a pulley upon the shaft of the lower pressure 35 roller 11. Said pulley 30 also supports one end of a belt 31 leading to the rewinder 26 and passing about a pulley 32 coaxial with the same. The rewinder and the pressure rollers are thus driven at the same relative 40 speed causing the run of paper to be drawn evenly at a constant rate past the ironing rollers 5, through the bath of dye, between the pressure rollers, through the drying oven and subsequently through the cooling chambers until rewound upon the roll 26 in 45 finished condition.

Obviously, if desired, the dyed and cooled run of paper might be cut into sheets after leaving the cooling chambers, rather than 50 rewound into roll form.

The paper resulting from the practice of my method has great brilliancy and depth of color, and is uniform in shade and tone throughout the entire length.

Having now clearly described my invention and the method involving the same, I desire it to be understood that my invention is not limited to the particular embodiment shown, but is commensurate in scope with 60 the following claims.

I claim—

1. In an apparatus for producing colored nature papers, a rotatable holder carrying a roll of uncolored strip paper, means for 65 drawing out the paper from the roll and

ironing the same, a dye tank, a plurality of hard-surfaced pressure rollers between which the paper is passed after leaving the solution of dye, a box confining a body of heated air through which the paper travels free from contact with any supporting or other surface while said paper is wet with dye, a series of rollers alternately over and under which the dried paper is drawn, a winding roll upon which the finished paper is rewound, and means for rotating said pressure rollers and said winding roll at the same relative speed whereby the strip paper is continuously fed at a constant rate of travel.

2. In an apparatus for producing colored nature papers, in which paper in strip form is drawn through a dye tank, a rotatable holder for an uncolored roll of said paper, a series of ironing rollers intermediate said holder and the tank, a plurality of hard-surfaced rollers for pressing out excess color, a hot-air box in which the paper is dried before contact with any supporting or other surface after leaving said hard-surfaced rollers, cooling chambers through which the dried colored paper is festooned, a rewinding roller, and means for rotating said hard-surfaced rollers and said rewinding roller at the same relative speed.

3. In an apparatus for producing colored nature papers in which a strip of uncolored paper is continuously fed from a roll, a series of ironing rollers, a dye tank through which the paper is drawn, pressure rollers for removing excess dye from the paper, a hot-air box through which the paper passes without contact with any surface while said paper is wet with dye, cooling chambers through which the paper is festooned, and a winder 100 for rewinding the dried and cooled colored paper.

4. In an apparatus for producing colored nature papers in which a strip of uncolored paper is drawn from a roll, a series of ironing rollers 5, a tank 7, a pair of color-regulating pressure rollers 10, 11, a hot-air box 20 for drying the colored paper, cooling chambers 24 through which the dried paper is successively drawn, and a winder 26 for 115 rewinding the finished paper.

5. The method of producing colored nature papers in roll form which consists in drawing out from a roll a strip of uncolored paper, in passing said strip at a constant speed through a solution of dye mixed with a small proportion of glycerine, in pressing from the paper the dye in excess of a predetermined amount, in completely drying the travelling paper before it has contact with 120 any supporting or other surface, in subsequently cooling the dry dyed paper, and finally in winding it into a roll.

6. The method of producing colored nature papers in roll form which consists in 125

- rotatably mounting a roll of uncolored paper, in drawing out and ironing said paper, in passing said paper at a constant speed through a dye solution, in removing and preserving any excess dye solution above a predetermined amount, in subsequently completely drying the paper by passing it through a body of heated air and before contact of said paper with any supporting or other surface, in subsequently cooling the dried colored paper, and finally in rewinding the paper into a roll.
- 5 In testimony whereof, I have signed my name to this specification.
- 10
- THOMAS MERCER ATKINSON.
